CLAIM

The ornamental design for a connector, as shown and described.

DESCRIPTION

FIG. 1 is a front view of my design;

FIG. 2 is a rear view thereof;

FIG. 3 is a top view thereof;

FIG. 4 is a bottom view thereof;

FIG. 5 is a right side view thereof; and,

FIG. 6 is a left side view thereof.

The broken lines in the drawings depict portions of the connector that form no part of the claimed design.
